UNITED STATES PATENT OFFICE.

JESSE STEELE, OF ROANOKE, VIRGINIA.

MARKER-BRACKET FOR RAILROAD-CARS.

1,317,995.

Specification of Letters Patent.

Patented Oct. 7, 1919.

Application filed March 21, 1919. Serial No. 283,990.

To all whom it may concern:

Be it known that I, JESSE STEELE, a citizen of the United States, residing at Roanoke, in the county of Roanoke and State of Virginia, have invented a new and useful Marker-Bracket for Railroad-Cars, of which the following is a specification.

The object of my invention is to provide an improved emergency marker bracket 10 which may be readily fastened to one of the grab irons of a railroad car; and which may be manufactured at relatively small cost and adapted for use under varying conditions by reason of its adjustability.

15 I attain these and other objects of my invention by the mechanism illustrated in the accompanying drawings, in which—

Figure 1 is a side elevation of the invention, the grab iron being shown in sections;

20 Fig. 2 is a top plan;

Fig. 3 is a front view; and

Fig. 4 is a section on line 4—4 of Fig. 1.

Referring to the accompanying drawings, I provide a main plate 1, to which 25 is hingedly mounted a top plate 3 by means of hinge pin 5. Plate 1 is provided with a socket portion 2, and plate 3 with a corresponding socket portion 4 to engage the grab iron 14. I provide a suitable wing bolt 6 for adjustably securing the plates 1

and 3 to the grab iron 14. I further provide a suitable depending rib 7, in which is adjustably mounted the adjusting screw 8, which is provided with a head 9 adapted

35 to abut against the end of the car 15, as indicated in Fig. 1, to support the marker bracket in substantially horizontal position. Adjusting screw 8 is locked in position by a suitable wing nut 13 which abuts against

40 the end of rib 7. Main plate 1 is provided with a suitable head 11, having a downwardly tapering channel extending there-

through, and being further provided with a slot 12 extending only part way to the 45 bottom of the bracket head 10, as shown in Fig. 3. A plurality of thumb bolts 6 are preferably provided as shown in Fig. 4.

The bracket is readily applied to the 50 grab iron of a freight car by clamping portions 2 and 4 of plates 1 and 3 over the grab-iron, tightening bolts 6, and adjusting the adjusting screw 8 so that its head 9 will engage the end of the car and support the marker bracket and marker lamp

and flag which it may carry in their proper 55 position at the end of the car. The marker bracket is to be used in case of a car being attached to the rear of a train and no receptacle is provided for marker lamps or flags to indicate the rear of the train. It 60 is made to hold the standard marker lamp now used; and it is intended to supplant the flag now used and save the expense of same, as the marker lamp can be used for night or day to indicate the rear of the 65 train. In case an express car is picked up and no receptacle provided for markers, the trainman is usually given a flag to tie to the car and in most cases he will fail to take it down, and the railroad is 70 thereby the loser. At the present time railroad trainmen are frequently forced to hunt for a piece of wire or cord with which to tie the marker lamp to the rear of cars, with the result that besides annoyance and 75 delay, in fastening the lamp, there is usually a disastrous termination of the effort for the lamp which is often broken by knocking against the car. My emergency marker bracket is so constructed as to permit 80 of its convenient and quick attachment to any size grab iron on any railroad car, and provides a safe means of supporting the marker lamp.

What I claim is:

1. In a marker bracket for railroad cars, hinged plates having socket portions adapted to engage a grab iron, a marker bracket head carried by one of the plates, a rib depending from the lower 90 plate, and an adjusting screw mounted in said rib, adapted to abut against the end of the car to hold the marker bracket in substantially horizontal position.

2. In a marker bracket for railroad cars, 95 hinged plates shaped to engage a grab iron, wing bolts adjustably securing said plates in adjusted relation over the grab iron; a marker bracket head shaped to carry a marker lamp, a depending rib, an adjusting 100 screw mounted in said rib and having its head abutting against the end of the railroad car when in adjusted position, and a wing nut adapted to lock the adjusting screw in fixed position, for the purposes de- 105 scribed.

JESSE STEELE.
